UNITED STATES PATENT OFFICE

2,077,808

WINDOW

Edmund Peremi and Louis Toth, Manhasset, N. Y.

Application April 6, 1935, Serial No. 14,965

18 Claims. (Cl. 189—64)

This invention relates to windows, and more particularly to windows of the casement type. The invention is in the nature of an improvement upon the inventions disclosed and claimed 5 in my Patent No. 2,060,525 dated November 10, 1936 for Window construction and my Patent No. 1,999,208 dated April 30, 1935 for Window construction.

General objects of the invention are to provide a frame structure which may be standard for various installations, to provide a frame which may be light but which will, nevertheless, have the necessary strength, to provide means for thoroughly and effectively sealing the sashes at all points, and to provide a structure which is capable of rapid, easy, and economical assembly.

It is an important object of the invention to provide a window construction which is adaptable to a wide variety of installations and which employs a minimum number of different metallic shapes.

It is a feature of the invention that provision is made for a frame subdivided into panels each adapted to receive either a stationary sash or a sash hinged to swing outward, together with adapter means to enable a sash to be mounted to swing inward if desired.

A further feature of the invention has to do 30 with a form of stile or rail construction employed where two swinging sashes come together, the arrangement being such that a rigid juncture is formed and the joint is thoroughly sealed without the necessity of employing a mullion or transom bar thereat.

Another feature of the invention is that provision is made for the seating of spring clips which hold the panes in place by the form of the frame and sash bars so that the clips may 40 be readily sprung into place and securely retained without any shop fabricating whatever.

A further feature of the invention has to do 45 with facilitating the removal and replacement of sash sealing members employed in the frame. Each sealing member desirably comprises a pair of angularly related resilient legs. The frame is adapted to receive and imprison the sealing strip. Provision is made of a cut out or recess 50 behind the vertex portion of each sealing member whereby the sealing member may be forced free by pressing the vertex portion into the recess.

Other objects and advantages will hereinafter 55 appear.

In the drawings forming part of this specification,

Fig. 1 is a fragmentary elevation of a portion of a building wall having a window embodying features of the present invention incorporated 5 therein;

Fig. 2 is a fragmentary, horizontal, sectional view taken on the line 2—2 of Fig. 1 looking in the direction of the arrows, the view being broken away intermediate its ends, and the structure being diagrammatically illustrated at the right hand side of the figure in dot and dash lines;

Fig. 3 is a fragmentary, vertical, sectional view taken on the line 3—3 of Fig. 1 looking in the 15 direction of the arrows;

Fig. 4 is a fragmentary, sectional view taken on the line 4—4 of Fig. 1 looking in the direction of the arrows, the structure shown being broken away intermediate its ends for compactness of 20 illustration;

Fig. 5 is a fragmentary, horizontal, sectional view taken on the line 5—5 of Fig. 1 looking in the direction of the arrows, and the view also includes a dotted line showing of the meeting 25 sash rails when the sashes are in a partly opened condition;

Fig. 6 is a fragmentary, horizontal, sectional view taken on the line 6—6 of Fig. 1 looking in the direction of the arrows; and

Fig. 7 is a fragmentary, sectional view on the line 7—7 of Fig. 1, looking in the direction of the arrows.

In Fig. 1 the building wall 1 is shown as having mounted therein a frame 2. The frame is 35 subdivided into side panels 3, a central panel 4, and upper and lower transom panels 5 and 6. The frame comprises sub-sill, jamb and header bars 7, which are steel angle bars and which are mounted in the wall of the building. These bars 40 surround the frame proper and are connected to one another to constitute a rigid reinforcing frame. The frame proper comprises head, sill and jamb bars 8 which are all of the same shape in cross-section to present toward the panels of 45 which they form boundaries a channel construction adapted to be employed for the mounting of either stationary sashes or outwardly swinging sashes. The frame also includes transom bars 9 and mullion bars 10 which are also like 50 one another and which also present toward the bounded panels a channeled form of the same shape as that presented by the head, sill and jamb bars.

Each of the head, sill and jamb bars comprises 55

an outwardly extending flange 11 transverse to the plane of the window which tapers in thickness to provide a dove-tail recess between itself and the wall proper for the reception and retention of caulking material 12. Each frame bar comprises a flange 13 disposed in a plane parallel to the plane of the window. The flanges 13 of all of the head, sill, Jamb, mullion and transom bars are disposed in a common plane. Each flange 13 is provided with an inwardly extending lip 14, the purpose of which will be made clear presently. Each bar includes a web 15 which extends inward at a right angle to the plane of the window, an inner flange 16 parallel to the plane of the window, and an outwardly extending lip 17 at the extremity of said flange.

The four bars bounding a panel may be employed for mounting a stationary window light, the mode of mounting being illustrated at the left-hand end of Fig. 2. A stationary light 18 is set with its margins resting against the lips 17 and overlapping the flanges 16. Spring clips 19 are inserted in the bars to hold the light in place. Each spring clip 19 comprises a straight leg 20 having a U-shaped portion 21 at one end thereof and a reverse U-shaped portion 22 beyond the portion 21. The resilient U-shaped portion 22 bears against a face of the light and the leg 19 is inserted with the portion 21 pushing into the space between the edge of the light and the web 15. The straight edge of the leg 20 is held in the notch formed behind the lip 14. It will be observed that the portion 21 as shown in Fig. 2 is spaced a substantial distance away from the flange 16. The purpose of this arrangement is to enable the clip to be thrust far enough in toward the flange 16 by means of a screw driver or other suitable implement to cause the straight edge of the leg 20 to pass around behind the lip 14. When the implement is withdrawn the resiliency of the portion 22 causes the leg 20 to travel away from the flange 16 so that the leg 20 becomes trapped behind the lip 14. The spacing lips 17 afford extra clearance to facilitate the assembly in the manner described.

As shown, the stationary light comprises a series of panes with muntin bars interposed between adjacent panes. The stationary light is rimless, the outer margins of the panes being seated against the lips 17 of the flanges 16 of the frame proper. The lips 17 may be notched to receive the muntin bars, and the muntin bars may be spot welded to the flanges 16.

Each transom and mullion bar is provided with a recess 23 in its inner face which is adapted to receive a steel reinforcing bar 24. The bar 24 may be made of any width desired according to the strength which it is required to have. The bar 24 is provided with a cap or cover 25 of non-corroding metal and the bar together with the cap is fitted into the recess 23 and secured therein by screws 26 threaded through the webs 15 and into threaded bores which are provided in the bar 24. The cap 25 is provided with an extension lip extending inward from its inward edge to form screen rabbets.

The central panel 4 of the window is shown as having a pair of swinging sashes 27 and 28 mounted therein in complementary relation and supported by hinges 29 and 30 to swing outward about vertical axes.

The sashes 27 and 28 are constructed and arranged to interfit and form a strong connection with one another when closed, without the necessity of employing any mullion bar between them.

Provision is also made for effectively sealing the sashes both at the meeting joint and at the joints formed between them and the side mullions and transom bars.

Each transom bar 8 and mullion bar 10 bounding the panel 4 has inserted in its channel portion a sealing strip 31 comprising a straight leg 32 and a bent leg 33. The sealing member is of resilient sheet metal and its legs form an acute angle with one another. The vertex portion of the sealing member 31 is received in the angle formed behind the lip 14, and the leg 32 is long enough to extend behind the lip 17. Thus the leg 32 which is free to yield when engaged and pressed by the sash is limited in its outward movement by engagement with the inner face of the lip 17. The free margin of the leg 32 normally engages the lip 17 and seals the space bounded by the sealing members against ingress of dirt. The web 15 is provided with a notch 34 behind the vertex portion of the sealing member 31, so that should it become necessary or desirable to remove the sealing member 31 for any reason this may be accomplished by applying a tool to press the vertex portion of the sealing member into the notch 34. This action causes the leg 33 to move clear of the lip 17 so that the sealing member can be pulled out.

Each sash comprises tubular rails 35 and 36. The rail 35 adjacent the hinge is provided with a flange 37 for engaging the outer face of the mullion bar 10, a beveled wall 38 for engaging the leg 33 of the sealing member 31, and a wall 39 for engaging the lip 17. The channel portion of the bar 10 forms an air space when the sash is closed which is sealed at its outer and inner extremities and is subdivided by the engagement of the leg 33 of the sealing member with the beveled face 38 of the sash bar. The top and bottom rails of the sash are of the same shape as the rail 35 and are similarly sealed.

The rails 36 are of a somewhat different form from the rails 35. The rail 36 forming a part of the sash 27 has a dove-tail groove 40 which receives and holds a sealing and striking bar 41. The bar 41 includes divergent flanges 42 which form a dove-tail for fitting into the dove-tail groove of the rail 36. The bar 41 also includes at the inner side of the window a flange 43 which is spaced inward a little from the inner face of the rail 36 and which is provided at its ends with lips 44 and 45 forming shoulders. A resilient sheet metal sealing member 46 is clamped between the rail 36 and the bar 41 toward the outer side of the window and extends obliquely inward so that its inner end overlaps the shoulder 45 and is limited by said shoulder when the sashes are swung apart. The flange 43 overlaps both sashes at the inner sides thereof when the same are closed, the shoulder 45 forming a supporting and sealing abutment for engagement with the sash rail 36 of the sash 28.

A striking and sealing bar 47 generally similar in construction to the bar 41 is mounted upon the rail 36 of sash 28 in the same manner that the bar 41 is mounted on the rail 36 of the sash 27. The bar 47 includes a flange 48 at the outer side of the window which overlaps both sashes when the same are closed, and which bears against the outer face of the sash 27 to form a sealing joint. The flanges 43 and 48 cooperate to render the sash joint strong and rigid when the sashes are closed and also with sealing member 46 to thoroughly seal the joint. They define an air space between the sashes which is subdivided by en-

gagement of the sealing member 46 with the face of the bar 41.

The rails 35 and 36 are provided with dove-tail grooves 49 in their faces which bound the pane receiving panels. Spring clips 19 are employed in conjunction with these dovetail grooves for securing the panes 50 in place in the same manner that the clips 19 are employed in Fig. 2 for securing a stationary light in place.

10 The sashes are subdivided into pane panels by muntin bars 51 which are generally T-shaped in cross section. The stem of each muntin bar is provided at its opposite sides with short flanges 52 which extend obliquely toward the pane seat 15 to form retaining means for clips 19 and for putty applied to the pane, and to form a scribing guide for puttying.

The frame and sash construction employed is such that stationary or outwardly swinging sashes 20 may be employed in any of the panels as desired.

It is a further feature, however, that provision may be made for mounting a panel to swing inward by effecting a slight and inexpensive alteration of the frame. This feature is best illustrated in Figs. 2 and 4 in which the lower sash in the panel 6 is mounted to swing inward, being hinged at its lower edge. For adapting the frame for this kind of sash mounting, the lip 14 and flange 16 which bound the panel 6 are cut away 25 flush with the face of the web 15. Filler or adapter bars 53 are then applied to the bars which bound the panel, being secured thereto by means of screws 54. Each bar 53 is substantially the same in cross section as one of the bars 8 30 but it is set in the opposite direction, that is with its long flange 16a and its lip 11a at the outer side of the window and with its shorter flange 13a at the inner side. The web 15a is provided with ribs 55 against which the straight leg of a sealing member 31 bears. Behind the vertex portion 40 of the member 31 and adjacent the inner rib 55 a recess is formed for enabling the sealing member 31 to be removed in the manner already described. The web 15a is provided with a rib 56 which fits into the recess 34 of the web 15 and serves to accurately seat adapter members 53. The sash 57 is mounted to cooperate with the frame adapter members 53 in the same manner that the other swinging sashes, particularly the 45 transom sash 58, cooperates with the normal frame members.

The description just given with reference to the sash 57 does not, however, apply to the bottom sill which is left in its original form. The 55 flange 16 of the sill has hinges 59 attached to it, and the bottom rail of the sash is of a form complementary to that of the other sash rails, the flange 31a being disposed to engage against the outer face of the sill flange 13 at the outer side of 60 the window.

While we have illustrated and described in detail certain preferred forms of our invention, it is to be understood that changes may be made therein and the invention embodied in other 65 structures. We do not, therefore, desire to limit ourselves to the specific constructions illustrated, but intend to cover our invention broadly in whatever form its principles may be utilized.

We claim:

70 1. In a window of the casement type, in combination, a frame including frame bars of combined channel and angle form having short flanges at the outer side and relatively long flanges at the inner side adapted to have sealing engagement with the inner and outer faces of an

outwardly swinging sash and an adapter frame of like form adapted to be used as a replacement for said flanges by having the reverse relative arrangement of the long and short flanges to co-operate with an inwardly swinging sash. 5

2. In a window of the casement type, in combination, a frame including frame bars each of combined channel and angle form and having a lipped short flange at the outer side and a relatively long flange at the inner side connected 10 by a transverse wall, said wall having a notch formed in it adjacent the short flange and adapter bars of like form adapted to be used as replacements for said flanges by having the reverse relative arrangement of the long and short 15 flanges to co-operate with an inwardly swinging sash, each adapter bar having a rib for fitting into the notch of the associated frame bar when the flanges of the frame bar are removed to control the position of the adapter relative to 20 the frame bar and provide a rigid construction.

3. In a window of the casement type, in combination, a frame including frame bars each of combined channel and angle form and including relatively long and short flanges at the inner and outer sides thereof and a connecting transverse wall, said flanges having lips at their extremities, a V-shaped sheet metal member imprisoned in the channel with its vertex directed towards the side of the window to which the sash swings in 25 opening and retained behind the lip of one flange and the free end of its sash engaging leg disposed behind the lip of the other flange and a swinging sash having parallel faces for simultaneously engaging the outer faces of the long and short 30 flanges and an oblique connecting wall for engaging and deflecting the free leg of the sealing member. 35

4. In a window of the casement type, in combination, a frame including frame bars each of combined channel and angle form and including relatively long and short flanges at the inner and outer sides thereof and a connecting transverse wall, said flanges having lips at their extremities, a V-shaped sheet metal sealing member imprisoned in the channel with its vertex 40 behind the rib of one flange and the free end of its sash engaging leg disposed behind the lip of the other flange and a swinging sash having parallel faces for simultaneously engaging the outer faces of the long and short flanges and an oblique connecting wall for engaging and deflecting the free leg of the sealing member, the transverse connecting wall of each frame bar having a notch or groove adjacent the short leg 45 to facilitate removal of the sealing member when desired. 50

5. In a casement window, the combination with a pair of swinging sashes having meeting rails of oppositely disposed T-shaped striking and sealing bars carried by the meeting rails of the respective sashes, one arranged to overlap both sashes at the inner side of the window and the other arranged to overlap both sashes at the outer side of the window and a resilient sealing member 60 affixed at one end to the leg of one of the T-shaped members and disposed to be engaged and deflected by the leg of the other T-shaped member when the sashes are closed. 65

6. In a casement window, the combination with 70 a pair of swinging sashes having meeting rails of oppositely disposed T-shaped striking and sealing bars carried by the meeting rails of the respective sashes, one arranged to overlap both sashes at the inner side of the window and the 75

- other arranged to overlap both sashes at the outer side of the window and a resilient sealing member affixed at one end to the leg of one of the T-shaped members and disposed to be engaged and deflected by the leg of the other T-shaped member when the sashes are closed, and a rib on the cross of the T-shaped member which carries the sealing member for limiting movement of the free end of the sealing member away from the leg of said T-shaped member and for guarding the edge of the sealing member.
7. In a window, in combination, a muntin bar of T form, the cross of the T forming pane seats and the stem of the T having short divergent flanges at opposite sides thereof which point toward the pane seats and define retaining notches or grooves and means interlocked with the retaining notches for holding the panes in place.
8. In a window, a frame comprising division bars of non-corroding metal, each division bar being of channel form, a reinforcing steel bar set in the channel and fastenings extending through the channel walls and into the reinforcing bar for affixing it to the frame.
9. In a window, a frame comprising division bars of non-corroding metal, each division bar being of channel form, a reinforcing steel bar set in the channel, a cover of non-corroding metal partially embracing the reinforcing bar and fastenings extending through the channel walls and the walls of the cover and into the reinforcing bar.
10. In a window, a frame comprising division bars of non-corroding metal, each division bar being of channel form, a reinforcing steel bar set in the channel, a cover of non-corroding metal partially embracing the reinforcing bar and fasteners driven through the channel walls and into the reinforcing bar.
11. In a window, a swinging sash comprising a meeting rail bar of rectangular tubular formation, said bar having dove-tail grooves formed in opposite faces thereof, one of said grooves being provided for receiving putty and the other for receiving and interfitting with a striking bar.
12. In a window, a swinging sash comprising a meeting rail bar of rectangular tubular formation, said bar having dove-tail grooves formed in opposite faces thereof, one of said grooves being provided for receiving putty, and a striking bar having divergent flanges adapted to fit in the other dove-tail groove, said flanges being deformable so that they may be spread apart to cause them to have a driving fit with the tubular bar, the striking bar being secured to the tubular bar without the aid of extraneous holding means.
13. In a window, a swinging sash comprising a meeting rail bar of rectangular tubular formation, said bar having dove-tail grooves formed in opposite faces thereof, one of said grooves being provided for receiving putty, and a striking bar having divergent flanges adapted to fit in the other dovetail groove, said flanges being deformable so that they may be spread apart to cause them to have a driving fit with the tubular bar, the striking bar being secured to the tubular bar without the aid of extraneous holding means, and a resilient sealing strip overlying the striking bar and having a flange clamped between the tubular bar and the striking bar.
14. In a window, a frame composed of channeled members all of the same cross sectional shape, said channeled members being adapted for mounting sashes to swing outward or for mounting stationary window lights, and means for adapting said members for mounting sashes to swing inward.
15. In a window, a frame adapted for the mounting of stationary window lights or swinging window sashes, comprising channeled rails of identical cross sectional shape, each rail having a flange extending parallel to the plane of the window with a lip at the inner edge thereof, said lip adapted to serve as a retaining means for a sealing member when a swinging sash is used but being adapted to be notched out to interfit with muntin bars when a stationary light is used.
16. In a window, in combination, a frame composed of channeled bars, a swinging sash, a V-shaped resilient sealing member held in a channeled frame bar with its vertex disposed in the direction in which the sash opens and with one of its legs disposed to intersect at an acute angle the path traversed by the sash in closing said frame bar having a lip to cover and guard the free edge of said leg and hold the sealing member under compression when the sash is open, and said sash having a rail or stile for engaging said leg of the sealing member intermediate its ends and at a portion remote from the vertex thereof to press against said leg of the sealing member and further compress the same.
17. In a window, in combination, a non-ferrous frame having channeled division bars, reinforcing steel bars secured in the channels of said division bars, and covers of non-corroding sheet metal for said reinforcing bars secured in the channels, said covers being formed with lips to define screen seats.
18. In a window of the casement type, in combination, a frame and a sash pivoted to swing into and out of closed position therein, said frame and sash including pairs of cooperating members adapted to effect a tight closure of the window when the sash is closed, one member of a pair of members comprising a channel having its open side facing its cooperating member, said channel having a narrow flange with a marginal lip facing the interior of the channel, and a wide flange having a marginal lip also facing the interior of the channel, and a generally V-shaped resilient sheet metal sealing member held in said channel with one leg of the V resting against the bottom of the channel and the vertex engaged beneath the lip on the narrow flange of the channel, and with the other leg of the V extending diagonally from the vertex towards the lip on the wider flange of the channel, said resilient sealing member being normally held under substantial stress by engagement between the free edge of said second leg and the lip on the wider flange of said channel when the sash is open; and the other member of said pair of cooperating members of the frame and sash respectively having a surface adapted to engage and seat against the edge of the lip on the wider flange of said channel and a surface adapted to seat against the outer surface of said narrower flange on said channel and a surface between said two first mentioned surfaces adapted to engage the outer surface of the second leg of said V-shaped resilient sealing member near the free edge of the latter when the sash is closed and to hold said second leg of the resilient sealing member in a position in which it is retracted from its normal position in engagement with the inner surface of the lip on the wider flange of said channel.
